UNITED STATES PATENT OFFICE.

WILLIAM LOREN DAVIS, OF RENTON, WASHINGTON, ASSIGNOR OF ONE-HALF TO FRANK ARTHUR WILSON AND LAURA IRENE WILSON, OF SEATTLE, WASHINGTON.

BUCKLE.

Application filed June 3, 1925. Serial No. 34,669.

This invention relates to a buckle, the general object of the invention being to provide a buckle which will hold the belt or strap against slipping after the parts are properly 5 adjusted, and which will render unnecessary the punching of holes in the belt or strap.

Another object of the invention is to so form the parts that the belt can be easily and quickly unfastened when desired.

10 This invention also consists in certain other features of construction and in the combination and arrangement of the several parts, to be hereinafter fully described, illustrated in the accompanying drawings and 15 specifically pointed out in the appended claim.

In describing my invention in detail, reference will be had to the accompanying drawings wherein like characters denote like 20 or corresponding parts throughout the several views, and in which:—

Figure 1 is a perspective view of the improved buckle.

Figure 2 is a view showing the device in 25 use.

Figure 3 is a section on line 3—3 of Figure 2.

In these views, 1 indicates the side pieces 30 of the buckle, 2 the end piece which is rounded to receive the looped end of the belt A which is permanently fastened to the buckle and 3 indicates a plate which fastens the opposite ends of the side pieces together. This plate is slightly inclined from the horizontal 35 and is located adjacent one edge of the buckle frame. The front part of the frame or that part to which the plate 3 is attached, is wider than the other part and the wide portions of the side pieces are provided 40 with inclined slots 4, one in each side piece and the slots incline in an opposite direction from the plate 3. A bar 5 has its reduced end 6 engaging said slots and the under face of said bar may be provided with the points 45 7 for penetrating the tongue or loose end of the belt when the same is placed in the buckle. The tongue or loose end of the belt is passed along the outer face of the plate 3 and is then looped and passed back along the

inner face thereof between the plate and the 50 bar, the bar being pushed to the high or outer ends of the slots in order to permit the tongue to be passed between the two parts. The tongue is pulled through a sufficient distance to make the belt tight about the waist 55 and then the bar is pushed downwardly so as to clamp the tongue between the bar and the plate. This will firmly hold the tongue against movement and thus hold the belt in adjusted position. When the belt is to be 60 removed, the tongue is pulled upon and then the bar moved outwardly so that it will release the tongue and then the tongue can be pulled from the buckle.

From the foregoing, it will be seen that I 65 have produced a buckle of a very simple construction and one which will firmly hold the belt against slipping. It also renders unnecessary the punching of holes in the belt. 70

It is thought from the foregoing description that the advantages and novel features of my invention will be readily apparent.

I desire it to be understood that I may 75 make changes in the construction and in the combination and arrangement of the several parts, provided such changes fall within the scope of the appended claim.

What I claim is:—

A belt buckle of the character described 80 comprising parallel side portions having reduced ends, a rounded end piece connecting the reduced ends and adapted to have one end of a belt secured thereto, an inclined plate disposed between the opposite ends of 85 said side portions which are provided with inclined slots disposed above said plate, a bar having reduced end portions slidably mounted within said slots, said belt having its free end looped about said plate and said 90 plate and slots being arranged in converging relation with respect to each other in a direction toward the rounded end piece, and penetrating points formed on the under face of said bar to grip the part of the belt looped 95 about said plate.

In testimony whereof I affix my signature.

WILLIAM LOREN DAVIS.
